Inventor:

E. S. Bennett

ERASTUS S. BENNETT, OF NEW YORK, N. Y., ASSIGNOR TO HIMSELF AND JUSTUS SMITH, OF SAME PLACE.

Letters Patent No. 83,822, dated November 10, 1868; antedated October 24, 1868

IMPROVED STIRRUP.

The Schedule referred to in these Letters Patent and making part of the same.

To all whom it may concern:

Be it known that I, ERASTUS S. BENNETT, of the city, county, and State of New York, have invented a new and useful Improvement in Safety-Stirrups; and I do hereby declare that the following is a full and exact description thereof, reference being had to the accompanying drawings, and to the letters of reference marked thereon.

The nature of my invention consists in constructing a stirrup with one side entirely open, and so forming the same that it will be impossible for the foot to become fastened or caught therein, in case the rider should fall or be thrown from his horse. The nature and frequency of horrible and usually fatal accidents from this cause is too well known to need more than simply a notice here. Being thrown from a horse cannot be looked upon as being conducive to health, but very rarely results fatally, or even seriously, but being thrown, and having the foot caught in the stirrup, is almost certain and terrible death.

To enable others skilled in the art to make and use my invention, I will proceed to describe its construction and operation.

The accompanying drawings represent the stirrup,

which should be made of steel, as delicately wrought as is compatible with sufficient strength.

D represents the strap, which passes through the upper end of the stirrup at c, a suitable aperture being made for the purpose.

The stirrup should be curved, nearly as shown at e, and should be reinforced or strengthened at a.

I have shown the point of the toe at B, slightly turned up, to prevent the stirrup slipping from under the foot. Any other device for this purpose may be substituted, as, for instance, a slight spring, fastened at its upper end, midway between c and e, its lower end just lapping over the toe of the stirrup, or it may be fastened underneath the stirrup, its loose end curving over the foot.

What I claim, and desire to secure by Letters Patent, is—

A stirrup made with one side entirely open, with a device for preventing its slipping, substantially as and for the purpose set forth.

E. S. BENNETT.
